Robert D. Gibson

by Edward Atty

UNITED STATES PATENT OFFICE.

ROBERT D. GIBSON, OF RAHWAY, NEW JERSEY, ASSIGNOR TO WESTERN ELECTRIC COMPANY, INCORPORATED, OF NEW YORK, N. Y., A CORPORATION OF NEW YORK.

TRANSMISSION REGULATION.

Application filed April 24, 1924. Serial No. 708,604.

This invention relates to transmission regulation and is particularly adapted for use in multiplex carrier current signaling systems.

5 An object of the invention is to stabilize the transmission in carrier signaling systems.

A related object of the invention is to utilize a signal channel of a multiplex carrier signaling system for the transmission of 10 a control or pilot current without interfering with the normal transmission of signals thereover.

Another object of the invention is to provide a flexible gain control system which 15 may be used in connection with any channel of a multiplex signaling system.

The invention is particularly applicable to signaling systems employing fairly high frequencies in which, as is well known, the 20 transmission characteristics of the transmission medium are subject to variations which render it difficult to maintain uniform signaling conditions.

Changes in the attenuation of the transmission medium of a system of the above 25 type produce corresponding variations in the over-all transmission equivalent of the system, and result in large fluctuations in the volume of a telephone or other message being 30 transmitted.

In order to overcome the effects of transmission variations in such systems, it is common practice to transmit a control or pilot current between the terminals of the system to indicate the condition of the transmission medium over which the telephone, telegraph, or other signals are transmitted. 35 This pilot current may be utilized at the receiving terminal to operate an indicating device or an automatic compensator, or, if desired, both indicating and compensating devices. Heretofore, it has been thought necessary to set aside one signal channel for the exclusive transmission of the pilot current, thus reducing the frequency range 45 available for the transmission of signals.

According to a feature of the invention, a control or pilot current is transmitted along with the voice or other signal modulation on one channel of a multiplex signaling system without in any way interfering with the normal transmission of signals over this channel.

More specifically, one channel of the system 55 is utilized for the transmission of a

pilot current of low frequency in addition to its normal use as a signal channel. The pilot current which may be of about 200 cycles frequency, is impressed upon the transmission medium at the transmitting 60 terminal along with the signal currents. At the receiving terminal, the pilot current is selected and is utilized to operate an indicating device to indicate changes in the transmission characteristics of the transmission 65 medium.

The invention will be described as applied to a multiplex carrier current telephone system, although it will be understood that it may also be applied to other signaling sys- 70 tems.

The drawing shows a diagrammatic illustration of a multiplex carrier telephone signaling system embodying the invention.

The system shown in the drawing is represented as comprising two terminal stations W and E, respectively, interconnected by the multiplex line ML. If desired, one or more repeater stations (not shown) may be connected to the line ML intermediate the terminal stations. 75

The terminal carrier current apparatus at station W comprises a plurality of transmitting channels TC₁, TC₂, etc., connected through a common transmitting circuit TL₁ 80 to the main line ML, and a plurality of receiving channels RC₁, RC₂, etc. connected through a common receiving circuit RL₁ to the main line ML. At station E, transmitting channels TC₃, TC₄, etc. are connected 85 to the main line through a common transmitting circuit TL₂, and receiving channels RC₃, RC₄, etc. are connected to the main line through a common receiving circuit RL₂.

Carrier currents are utilized for transmission over the line ML and are grouped as to their frequencies, the lower frequencies, as a group, being used for transmission from station W to station E, and the higher frequencies, as a group, being used for transmission from station E to station W. 95

Low pass grouping filters LP₁ and LP₂ at the respective terminal stations are each paired with a high pass filter HP₁ and HP₂. These filters serve to separate the directional 105 groups of carrier waves to the respective terminal transmitting and receiving circuits. These filters and each of the other filters shown throughout the system may be constructed and designed in accordance with 110

the principles laid down in the United States Patent to Campbell, No. 1,227,113, issued May 22, 1917.

For the purpose of the present description, a low pass filter may be taken to be any filter which transmits freely currents of all frequencies between zero and a pre-assigned limiting frequency, and suppresses the transmission of currents of all frequencies higher than said limiting frequency. Conversely, a high pass filter may be taken to be any filter which freely transmits currents of all frequencies higher than a pre-assigned limiting frequency and suppresses currents of all frequencies lower than said limiting frequency. Specific types of both of these kinds of filters are shown, for example, in Fig. 11 of the above mentioned Campbell patent.

20 Low frequency lines L_1 and L_2 which may be telephone lines or other types of signaling lines are associated with channels TC_1 , RC_1 , and TC_2 , RC_2 , respectively at station W for simultaneous and independent communication over the line ML with corresponding similar lines L_3 and L_4 which are associated with the channels TC_3 , RC_3 , and TC_4 , RC_4 at station E.

30 Each low frequency line is provided with a balancing artificial line or network N and with a differential repeating coil H, commonly known as a hybrid coil, for enabling independent transmission in the two directions between the line and the high frequency terminal apparatus.

The transmitting channel TC_1 at station W includes a modulator M_1 and a band filter TBF_1 , while transmitting channel TC_2 includes a modulator M_2 and a band filter TBF_2 . The receiving channel RC_1 at this station includes a demodulator D_1 and a band filter RBF_1 , while receiving channel RC_2 includes a demodulator D_2 and a band filter RBF_2 .

45 At station E, the transmitting channels TC_3 and TC_4 include the respective modulators M_3 and M_4 and band filters TBF_3 and TBF_4 , and the receiving channels RC_3 and RC_4 include the respective demodulators D_3 and D_4 and band filters RBF_3 and RBF_4 . The modulators and demodulators associated with the various transmitting and receiving channels throughout the system may be of any well known type, such as the balanced modulator and demodulator disclosed in the U. S. patent to Carson, No. 1,343,306, issued June 15, 1920.

60 The carrier system described above is of the type in which the carrier wave of each channel is suppressed from transmission when no signals are being sent, and when signals are being transmitted modulation component of the modulated wave are sent over the line, but no unmodulated components of the carrier wave are transmitted.

In order to reproduce the signal from modulated waves of this character, it is necessary that the carrier wave supplied to the demodulator at the receiver be of substantially the same frequency as the carrier wave which was suppressed at the transmitter. A system of this general character is described in connection with Fig. 49 of an article entitled "Carrier current telephony and telegraphy" by Messrs. Colpitts and Blackwell, published in the Transactions of the American Institute of Electrical Engineers, vol. 40, 1921. In the system illustrated in the accompanying drawing, however, it is assumed that the oscillators, such as TO_1 and RO_3 of the same channel are separately controlled to supply to the modulator and demodulator circuits, respectively, waves of the same frequency, although so far as the present invention is concerned, any type of frequency control may be used.

Carrier currents of the frequency assigned to channel TC_1 are supplied from a source TO_1 to the modulator M_1 wherein they are modulated by voice frequency currents or other signaling currents from the low frequency line L_1 . Carrier sources RO_1 , RO_2 and TO_2 are associated with the demodulators D_1 and D_2 and modulator M_2 at station W, while carrier current sources TO_3 , TO_4 and RO_3 , RO_4 are associated with the modulators M_3 , M_4 and demodulators D_3 , D_4 , respectively, at station E.

As noted above, the carrier current sources RO_1 , RO_2 , RO_3 and RO_4 are necessary to supply to the incoming side bands in each receiving channel, the carrier current which was suppressed at the transmitting end of the channel.

The various band filters associated with the transmitting and receiving channels at stations W and E may be of the band filter type disclosed in the Campbell patent, supra. These filters are so designed that they will transmit bands of frequencies in the neighborhood of the carrier frequency assigned to their particular channel, the bands being of sufficient width to accommodate the frequency variation due to the modulation of the basic carrier frequency by the signaling frequencies. The bands transmitted by the filters associated with the various transmitting and receiving channels should be sufficiently remote from the bands transmitted by the filters associated with the other channels to allow for frequency separation between the different channels.

At station W, an amplifier TA_1 is included in circuit with the common transmitting circuit TL_1 and low pass grouping filter LP_1 , and a receiving amplifier RA_1 is included in circuit with the common receiving circuit RL_1 and the high pass grouping filter HP_1 . At station E, transmitting amplifier TA_2 is included in circuit

with the common transmitting circuit TL_2 and grouping filter HP_2 , and receiving amplifier RA_2 is included in circuit with the common receiving circuit RL_2 and grouping filter LP_2 .

In accordance with the invention, a current of low frequency is transmitted as a pilot current along with the voice currents on any signaling channel of the system.

10 This pilot current which may be of about 200 cycles frequency, may be impressed upon any of the transmitting channels, such as TC_1 at station W, is combined in the modulator M_1 with the current of carrier 15 frequency supplied by the source TO_1 and is transmitted over the line to station E. At station E, the speech-and-pilot modulated current is selected by the band filter in a previously assigned receiving channel, 20 such as channel RC_3 , is demodulated, and the low frequency pilot current is then selected by a low pass filter and utilized to operate an indicating or recording device.

At station W, the pilot frequency current 25 is supplied from a pilot channel PC_1 connected to the low frequency line L_1 .

The pilot channel PC_1 includes a source of pilot current 10, a low pass filter 11 designed to transmit currents from zero to the 30 pilot frequency, and an adjustable current regulator 12. A thermocouple 14 may be included in the pilot channel PC_1 to supply a current proportional to the output of the pilot source 10 to an ammeter 13 which 35 serves to give a continuous indication of the pilot current. This enables the pilot current supplied to the modulator to be kept constant, as by varying the tap on resistance 12, either automatically or manually, to 40 keep the reading of the ammeter 13 constant.

At station E, a pilot channel PC_2 is connected to the low frequency line L_3 . The pilot channel PC_2 includes a low pass filter 45 15 identical to the low pass filter 11, an adjustable current regulator 16, amplifier 17, thermocouple 18, and an associated indicating device 19. The indicating device 19 may be any suitable type of meter such 50 as a galvanometer, and it is adapted to be operated by the direct current E. M. F. which is produced between the terminals of the thermocouple 18. This E. M. F. is a function of the amplitude of the alternating 55 current received by the pilot channel PC_2 , and any change in this alternating current produces a change in the direct current output of the thermocouple 18.

A high pass filter 20 is included in each 60 of the low frequency lines L_1 and L_3 . These filters are so designed that they transmit currents within the voice range but suppress the transmission of current of the unmodulated pilot frequency to the low frequency telephone apparatus associated with

these low frequency lines. These filters also serve to balance the impedance of the low frequency line L_1 , L_3 , for currents of the pilot frequency. It is obvious that the filters 20 are only required on the low frequency lines with which the pilot channel 70 is associated.

In operation, the pilot current of about 200 cycles supplied by the source 10 is transmitted through the low pass filter 11 in pilot 75 channel PC_1 to the low frequency line L_1 and thence to the transmitting channel TC_1 . The pilot current, along with speech currents from line L_1 , is combined in the modulator M_1 with the carrier current supplied by the source TO_1 , and one side band produced by this modulation, for example the lower side band, is transmitted through the filter TBF_1 , amplifier TA_1 , and low pass grouping filter LP_1 to the line ML . 80

At station E, the modulated wave is transmitted by the low pass grouping filter LP_2 and amplifier RA_2 to the common receiving circuit RL_2 and is selected by the band filter RBF_3 in the receiving channel 90 RC_3 . The receiving wave is then passed to the demodulator D_3 , where it is combined with a current of carrier frequency supplied by the source RO_3 to reproduce speech currents and a low frequency current of 95 200 cycles, the original pilot frequency. The detected speech currents are transmitted through filter 20 to the line L_3 . The pilot current is selected by the low pass filter 15, is transmitted through the amplifier 100 17 and is impressed upon thermocouple 18 in circuit with the meter 19.

If a change in line equivalent occurs anywhere in the system, the incoming pilot current changes and produces a change in 105 the potential derived from the thermocouple 18 which produces a corresponding deflection of the index of the meter 19.

If desired, an indicating device having a recording chart and associated mechanisms for making a permanent record may be employed instead of the meter 19. One type of apparatus for accomplishing this result is shown and described in the United States patent to Brewer, No. 1,356,804, issued October 26, 1920.

The meter 19 may also be employed to automatically control adjusting elements in the transmission circuit to compensate for changes of line equivalent. 120

The system described above provides means for indicating the transmission equivalent of the signaling system as a unit from voice frequency line to voice frequency line including all the carrier terminal apparatus. 125

It will be seen that by means of this invention, any channel of a carrier signaling system may be used to transmit a pilot current. Furthermore, since the pilot channel apparatus operates at a low frequency, diffi- 130

culties heretofore encountered due to high frequency terminal pilot circuits are eliminated.

The invention set forth herein is, of course, susceptible of various modifications and adaptations, and accordingly the invention is not to be considered as limited in any way except as defined by the scope of the appended claims.

10. What is claimed is:

1. In a transmission system, the method which comprises transmitting signal and control waves over a variable transmission medium as modulations of the same carrier wave, and utilizing the control wave so transmitted to indicate changes in the transmission characteristics of said medium.

2. In a transmission system, the method which comprises modulating a wave derived from a source at a sending station by speech waves, modulating a wave from said source by a control wave of a frequency below the essential speech frequencies, transmitting products of such modulation over a variable transmission medium, and utilizing the control wave so transmitted to indicate the transmission condition of said medium.

3. In a transmission system, the method which comprises modulating a wave derived from a source at a sending station by a signal wave, transmitting a product of the wave so modulated over one channel of a variable transmission medium, modulating a wave derived from said source by a control wave, transmitting the wave so modulated by the control wave over said channel, and utilizing the control wave so transmitted to indicate changes in the transmission equivalent of said medium.

4. In a transmission system, the method which comprises modulating a wave derived from a source at a sending station by a signal wave, transmitting a product of the wave so modulated over one channel of a variable transmission medium, modulating a wave derived from a source at said sending station by a control wave, transmitting a wave derived from such modulation over said channel, and utilizing the control wave so transmitted to indicate changes in the transmission equivalent of said medium.

5. In a transmission system, the method which comprises transmitting a signal wave over a variable transmission medium, superimposing a control wave upon said signal wave, and utilizing the control wave so transmitted to indicate changes in the transmission equivalent of said medium.

6. In a system for indicating variations in the attenuation of a transmission medium, a transmitting station including a source of carrier waves, means for modulating waves from said source in accordance with signal waves, means for also modulating waves from said source in accordance with a

control wave, means for impressing products of such modulation upon said transmission medium, means at a receiving station for separating the waves so transmitted, and an indicating device controlled by said control wave.

7. In a system for indicating variations in transmission equivalent, a variable transmission medium terminating in a transmitting and a receiving station, high frequency channels superposed on said medium at said stations, modulators included in the channels at said transmitting station, means for supplying high frequency waves to said modulators, means for supplying low frequency signal waves to said modulators, means for supplying a low frequency control wave of constant amplitude to one of said modulators, detector in the high frequency channels at said receiving station for combining the received modulated waves with locally generated waves to reproduce the low frequency modulating waves, means associated with one of said receiving channels to select the reproduced control wave, and an indicating device for indicating variations in amplitude of the received control wave.

8. In a system for indicating variations in transmission equivalent, a transmitting station and a receiving station, a variable transmission medium connecting said stations, a source of high frequency waves and a source of low frequency signal waves at said transmitting station, means for modulating a wave derived from said high frequency source by a wave derived from said low frequency signal source, means for impressing a product of the wave so modulated upon said transmission medium, a source of low frequency control waves at said transmitting station, means for modulating a wave derived from said high frequency source in accordance with a wave of constant amplitude derived from said low frequency control source, means for suppressing the unmodulated component of said high frequency wave, means at said receiving station for combining the received modulated waves with locally generated waves to reproduce the low frequency modulating signal and control waves, an indicating device at said receiving station, and means for impressing the reproduced control wave upon said indicating device.

9. In a multiplex carrier telephone system comprising at one station modulating circuits for producing and transmitting a single side band of each of a plurality of speech modulated waves of respective frequency ranges and at another station receiving circuits for deriving from each received side band a different speech wave, means for indicating changes in the transmission characteristics of said system including at said one station a source of low frequency currents,

80
